US00D572016S

(12) United States Design Patent
Kim et al.

(10) Patent No.: US D572,016 S
(45) Date of Patent:  Jul. 1, 2008

(54) DECORATIVE FILM FOR HOME APPLIANCES

(75) Inventors: Tae Il Kim, Gyeonggi-do (KR); Sang Yoon Lee, Seoul (KR); Kang Eui Cho, Seoul (KR); Jung Joo Yoo, Seoul (KR); In Hyeuk Choi, Seoul (KR); Jae Won Jeong, Seoul (KR); Seon Kyu Kim, Seoul (KR); Tae Hyun Sung, Seoul (KR)

(73) Assignee: LG Electronics Inc., Seoul (KR)

() Term: 14 Years

(21) Appl. No.: 29/282,031

(22) Filed: Jul. 10, 2007

(30) Foreign Application Priority Data

Jan. 25, 2007 (KR) 30-2007-0003425

(51) LOC (8) Cl. 05-06

(52) U.S. Cl. D5/37

(58) Field of Classification Search ..... D5/1, D5/2, 3, 5, 7, 8, 11, 13, 14, 15, 16, 19, 20, D5/23, 24, 25, 26, 27, 28, 30, 32, 35, 36, D5/37, 39, 43, 45, 47, 49, 50, 52, 53, 54, D5/55, 56, 57, 58, 59, 60, 61, 62, 63, 64, D5/65, 66, 99; D2/749, 994; D6/582, 583, D6/595, 596, 598, 603, 604, 605, 606, 608, D6/613, 616, 617, 619, 622; 428/17, 18, 428/151, 154, 156, 171, 187, 198, 199, 540, 428/542.2, 542.6, 904.4, 919; D24/124, D24/125, 126; D25/142, 152; 5/413 AM, 5/709; 162/109, 134, 140, 231; 156/148, 156/209; D7/396.4, 396.5
